UNITED STATES PATENT OFFICE.

JOHN M. CRAWFORD, OF CRAWFORD, OREGON.

PORTABLE WIRE FENCE.

No. 823,993.

Specification of Letters Patent.

Patented June 19, 1906.

Application filed October 25, 1905. Serial No. 284,352.

To all whom it may concern:

Be it known that I, JOHN M. CRAWFORD, a citizen of the United States, residing at Crawford, in the county of Yamhill and State of Oregon, have invented certain new and useful Improvements in Portable Wire Fences; and I do hereby declare the following to be a full, clear, and exact description of the invention, such as will enable others skilled in the art to which it appertains to make and use the same.

The principal object of my invention is to construct a wire fence which shall be portable, so that it may be readily and quickly transported from place to place as desired.

Another object is to provide means for stretching and maintaining the tension of wire fences, the materials for the manufacture of which are at hand on every farm, at no cost in money.

Another object is to provide a fence composed of few parts, thus rendering the device exceedingly simple, and which fence shall be thoroughly efficient in use and operation and comparatively inexpensive of manufacture.

With these objects in view and others appearing as the specification proceeds, the invention comprehends the novel construction, combination, and arrangement of parts of a device characterized by my invention, as will be hereinafter fully described in the specification, summed up in the claims, and illustrated in the accompanying drawings, in which—

Figure 1 is a view in front elevation of a wire fence with my invention applied thereto. Fig. 2 is a perspective view of an intermediate post.

Referring to the drawings in detail, A A designate two anchor-posts grounded in the earth, and which posts may be any suitable distance apart, as, say, forty rods.

B designates an intermediate post, of which there may be one or any number, as desired, depending, of course, upon the distance apart of the two anchor-posts A A. The posts B have desirably spikes b driven therein at a sharp slant or angle toward the top and bottom thereof for a purpose now appearing.

a designates the wire composing the fencing, the top wire passing over the upper spike b, (driven into the post B in a downward-slanting direction,) tending to support the fencing in proper position against sagging between the end posts A A, and the lower wire

of the fencing passing under the lower spike b, (driven into the post B in an upward-slanting direction,) whereby animals or the like are prevented from raising or elevating the fencing from the bottom, and, if desired, short pieces or lengths of wire b² or the like may be passed around the posts over the upper and lower wires a and the ends thereof twisted, thereby retaining these wires a 65 against displacement, but permitting longitudinal sliding movement of the wires a over the spikes b in the operation of tightening and tensioning the fencing.

At both ends of the wire fencing is a roller or stick a², preferably of cylindrical shape and of any suitable material, such as wood, and being disposed transversely of the wire fencing, the horizontal wires thereof being studded or otherwise suitably secured thereto. 70 The roller-stick is desirably longer than the width of the woven-wire fencing used, say, by eight inches. The roller-sticks a² are provided laterally with transverse openings a³ at different angles to each other, adapted to 75 be engaged by bars a⁴ (of iron or the like) in the operation of tightening or loosening the fencing after it has been set up for use.

When the fencing has been adjusted to a sufficient tension or adequately tightened by 85 the bars a⁴, a short wooden or other pin a⁵, passing through one of the openings a³ and engaging the post A, as shown in the drawings, temporarily prevents untightening or loosening of the fencing.

I preferably use wire a⁶, passing, preferably, at the top and bottom around posts A, and rollers a² (forming loops) to secure the wire fencing a against sidewise displacement, but permitting at the same time free rotary 95 movement of the rollers a² within the loops or bands a⁶ in the operation of tightening up the fencing. The ends of the pieces or lengths of wire forming the loops a⁶ are twisted, and thus the loops or bands are 100 easily removable.

When it is desired to transport the fence, all that has to be done is to withdraw the pins a⁵ and slip off the bands a⁶. The expeditious manner in which this can be accomplished makes my device exceedingly valuable.

The intermediate posts B are useful in that they assist in supporting the wire fencing and prevent sagging thereof, especially when the 110 anchor or end posts A are a considerable distance apart.

General directions for applying my invention.—Drive stakes for sighting on the line where the fence is to be erected. Place an anchor-post A firmly in the ground at the 5 point of beginning. Take a stick of timber a^2 (round fir-pole preferred) four or five inches in diameter and eight inches longer, say, than the width of the woven-wire fencing. Bore holes, desirably three holes, a^3 , 10 (preferably one and one-half inch,) at different angles through the stick a^2 and desirably about twelve inches apart. Take a roll of wire fencing to be used in constructing the fence and loosen the ends thereof and staple 15 the ends evenly to the stick a^2 , allowing, say, four inches of the stick to project above and four inches to project below the top and bottom wires, respectively. It requires less time to staple the wire fencing to the roller 20 post or stick a^2 than it would to an anchor-post, as is the usual way, because in stapling the woven-wire fencing to the roller post or stick the latter is lying on the ground with no consequent strain on the wires of the fencing, 25 which strain occurs when the wire fencing is stapled to an anchor-post, as is customary, and the roller post or stick a^2 when once stapled to the wire fencing is always ready for instant use, while the best wire-fence stretchers 30 now in use are heavy, cumbersome, and expensive, consisting of two heavy bars of iron or steel as clamps, which must be separated to admit the fence and then fastened together by numerous bolts, and these 35 stretchers now in use are too expensive to be owned by every farmer. Stand the stick a^2 , with the roller-fencing thus attached, up against the anchor-post A. Pass a piece or length of wire a^6 , say, three times, around the 40 anchor-post and the stick above the top wire of the fencing a and secure by twisting the ends together. Repeat this operation at the bottom of the post, only pass the wire a^6 below the bottom wire of the fencing a . Give 45 the stick a^2 a half-turn and insert a strong wooden pin a^5 in one of the auger-holes a^3 . Unroll the coil of fencing a along the line and staple another roller a^2 to the other end of the wire fencing a . Then take up all the 50 slack by pulling on the last-mentioned roller-stick a^2 and place at this point another anchor-post A. Place therearound two loops of wire a^6 and insert the stick a^2 therein at the top and bottom. Place intermediate anchor- 55 posts B as desired, say, thirty or forty feet apart. Drive slantingly downward a short heavy spike into each intermediate anchor-post B near the top thereof at the proper height for the top wire of the fencing a , which 60 top wire rests on the spike. Give the spike a sharp angle or slant, so that the fence will not slip off. Repeat this operation with all intermediate anchor-posts B. Now insert an iron bar a^4 of the desired length, in this in- 65 stance four or five feet, giving the necessary

lever purchase, in one of the auger-holes a^3 and turn the stick a^2 until the wires of the fencing shall have encircled the same, and then insert a wooden pin a^5 to prevent unwinding. Then go back to the first stick a^2 70 and turn it until the wires shall have encircled it. Then either stick a^2 may be turned by the iron bars a^4 until the wire fencing is brought to the proper tension and is adequately tight. Press the bottom wire of the 75 fencing a down hard at each intermediate anchor-post B and drive a spike above the lower wire with the proper slant to prevent the bottom wire from being easily displaced and to prevent animals or the like from raising or elevating the fence from the bottom. Wires b^2 may then be passed around the anchor-posts B, as shown, the pieces or lengths of wire b^2 being secured by having their ends twisted, thus further conferring stability 80 upon the structure. 85

Should the anchor-posts A sag, as they always will sooner or later from decay and other causes, with my invention applied the fence may be separated from the anchor-posts easily, the posts A straightened up or renewed, and the fencing retightened without cutting wires or drawing staples. The efficiency and value of this is obvious. With devices now in common use the staples must be 90 drawn from the anchor-posts, often resulting in the breaking of wires, and a stretcher procured, making a tedious and often expensive operation. 95

The usefulness of a wire fence is governed 100 largely by the tension thereof. The extreme cold of winter and the intense heat of summer will cause the fence to become slack and destroy its usefulness; but my invention admits of loosening for winter and tightening 105 for summer by a simple operation.

General directions for taking down fence for removal.—Remove the wooden pin a^5 from one of the roller posts or sticks a^2 , slip the roller-post out of the wire loops a^6 , lay roller post or stick with fencing attached on the ground, and continue along the line, disconnecting the fencing from intermediate anchor-posts B, letting the fencing lie on the ground. When the next roller-post is 115 reached, disconnect it from anchor-post, as before, and roll the fencing around it by rolling over and over to the place of beginning. Take up the anchor-posts. The fencing and posts are now ready to be removed to be set 120 up at another place without removing a spike or staple.

Having thus particularly described the nature and details of my invention, what I desire to secure by Letters Patent is— 125

1. A portable wire fence, comprising two upright anchor-posts supported at a distance apart, two upright rollers disposed between the posts and carrying therebetween wire fencing permanently secured to and engaging 130

the rollers, only; said rollers being removably connected with the posts, whereby they may be freely disengaged from the posts and, at the same time, carry with them the wire fencing secured thereto, without first removing the wires, or causing the wire fencing to become disengaged from the rollers to which it is secured.

2. A portable wire fence, comprising two upright anchor-posts supported at a distance apart, two upright rollers disposed between the posts and carrying therebetween wire fencing stapled to and permanently engaging the rollers, only; said rollers being removably connected with the posts, whereby they may freely be disengaged from the posts and, at the same time, carry with them the wire fencing secured thereto, without first removing the wires, or causing the wire fencing to become disengaged from the rollers to which it is secured.

3. A portable wire fence, comprising two upright anchor-posts supported at a distance apart, two upright rollers disposed between the posts and carrying therebetween wire fencing permanently secured to and engaging the rollers, only; said rollers being removably connected with the posts, whereby they may be freely disengaged from the posts and, at the same time, carry with them the wire fencing secured thereto, without first removing the wires, or causing the wire fencing to become disengaged from the rollers to which it is secured; and an auxiliary post disposed intermediate the said two posts and constructed to assist in supporting the wire fencing.

4. A portable wire fence, comprising two upright anchor-posts supported at a distance apart, two upright rollers disposed between the posts and carrying therebetween wire fencing permanently secured to and engaging the rollers, only; said rollers and posts being connected by removable loops, whereby the rollers may be freely disengaged from the posts and, at the same time, carry with them the wire fencing secured thereto, without first removing the wires, or causing the wire fencing to become disengaged from the rollers to which it is secured.

5. A portable wire fence, comprising two upright anchor-posts supported at a distance apart, two upright rollers disposed between the posts and carrying therebetween wire fencing permanently secured to and engaging the rollers, only; said rollers being removably connected with the posts, whereby they may be freely disengaged from the posts and, at the same time, carry with them the wire fencing secured thereto, without first removing the wires, or causing the wire fencing to become disengaged from the rollers to which it is secured; and means coöperating with the rollers for tightening the wire fencing and taking up slack thereof.

6. A portable wire fence, comprising two upright anchor-posts supported at a distance apart, two upright, transversely-perforated rollers disposed between the posts and carrying therebetween wire fencing permanently secured to and engaging the rollers, only; said rollers being removably connected with the posts, whereby they may be freely disengaged from the posts and, at the same time, carry with them the wire fencing secured thereto, without first removing the wires, or causing the wire fencing to become disengaged from the rollers to which it is secured; and bars engaging the transverse perforations of the rollers for tightening and taking up slack of the wire fencing.

7. A portable wire fence, comprising two upright anchor-posts supported at a distance apart, two upright, transversely-perforated rollers disposed between the posts and carrying therebetween wire fencing permanently secured to and engaging the rollers, only; said rollers and posts being connected by removable loops, whereby the rollers may be freely disengaged from the posts and, at the same time, carry with them the wire fencing secured thereto, without first removing the wires, or causing the wire fencing to become disengaged from the rollers to which it is secured; and bars engaging the perforations of the rollers for tightening and taking up slack of the wire fencing.

8. A portable wire fence, comprising two upright anchor-posts supported at a distance apart, two upright rollers disposed between the posts and carrying therebetween wire fencing permanently secured to and engaging the rollers, only; said rollers being removably connected with the posts, whereby they may be freely disengaged from the posts and, at the same time, carry with them the wire fencing secured thereto, without first removing the wires, or causing the wire fencing to become disengaged from the rollers to which it is secured; means coöperating with the rollers for tightening and taking up slack of the wire fencing; and means for temporarily holding the wire fencing in any adjusted or tightened position.

9. A portable wire fence, comprising two upright anchor-posts supported at a distance apart, two upright, transversely-perforated rollers disposed between the posts and carrying therebetween wire fencing permanently secured to and engaging the rollers, only; said rollers being connected with the posts by removable loops, whereby the rollers may be freely disengaged from the posts and, at the same time, carry with them the wire fencing secured thereto, without first removing the wires, or causing the wire fencing to become disengaged from the rollers to which it is secured; bars engaging the openings of the rollers for tightening and taking up slack of the wire fencing; and means for holding the

wire fencing in any such adjusted or tightened position.

10. A portable wire fence, comprising two upright anchor-posts supported at a distance apart, two upright rollers disposed between the posts and carrying therebetween wire fencing permanently secured to and engaging the rollers, only; said rollers being connected with the posts by removable loops passing around the posts and the rollers, whereby the rollers may be freely disengaged from the posts and, at the same time, carry with them the wire fencing secured thereto, without first removing the wires, or causing the wire fencing to become disengaged from the rollers to which it is secured.

11. A portable wire fence, comprising two upright anchor-posts supported at a distance apart, two upright rollers disposed between

the posts and carrying therebetween wire fencing permanently secured to and engaging the rollers, only; said rollers being connected with the posts by removable loops formed of short lengths of wire having their ends twisted, whereby the rollers may be freely disengaged from the posts and, at the same time, carry with them the wire fencing secured thereto, without first removing the wires, or causing the wire fencing to become disengaged from the rollers to which it is secured.

In testimony whereof I affix my signature in the presence of two subscribing witnesses.

JOHN M. CRAWFORD.
